UNITED STATES PATENT OFFICE

171,676

ASH TRAY OR SIMILAR ARTICLE

George Robert Woolsey, Norwalk, Calif., assignor
to U. S. Electrical Motors, Inc., Los Angeles,
Calif., a corporation of California

Application September 18, 1953, Serial No. 26,865

Term of patent 14 years

(Cl. D85—2)

To all whom it may concern:

Be it known that I, George Robert Woolsey, a citizen of the United States, and a resident of the city of Norwalk, in the county of Los Angeles, and State of California, have invented a new, original, and ornamental Design for Ash Tray or Similar Article, of which the following is a specification, reference being had to the accompanying drawing, forming a part thereof, in which:

Figure 1 is a plan view of an ash tray or similar article showing my new design; and

Figs. 2 and 3 are sectional views, taken along

planes indicated by lines 2—2 and 3—3, respectively.

I claim:

The ornamental design for an ash tray or similar article, substantially as shown.

GEORGE ROBERT WOOLSEY.
